C. Esten Beeler Inventor

UNITED STATES PATENT OFFICE.

ESTEN BEELER, OF NEW YORK, N. Y., ASSIGNOR, BY MESNE ASSIGNMENTS, OF ONE-FOURTH TO HERBERT BEELER, OF NEW YORK, N. Y.

BUBBLE-MAKING MACHINE.

1,167,619.

Specification of Letters Patent. Patented Jan. 11, 1916.

Application filed June 27, 1914. Serial No. 847,625.

To all whom it may concern:

Be it known that I, ESTEN BEELER, a citizen of the United States, residing at No. 400 West Fifty-eighth street, in the borough 5 of Manhattan, city of New York, State of New York, have invented a new and useful Bubble-Making Machine, of which the following is a specification.

My invention relates to improvements in 10 bubble making machines and the object of my invention is to produce bubbles in large quantities of a very dry nature in any size desired for display and theatrical illusions or other purposes.

15 I attain these objects by the mechanism illustrated in the accompanying drawing in which—

Figure 1 is a cross section taken on line 1—1 looking in the direction of arrow of Fig. 2; Fig. 2 is a plan view of the tank and 20 parts thereof; Fig. 3 is a longitudinal section taken on line 3—3 of Fig. 2 looking in direction of arrow; Fig. 4 is a perspective view of the entire apparatus.

25 Similar letters refer to similar parts throughout the several views.

The pipe A is the source of gas pressure supply, the tank B is a suitable container in a convenient form. The gas pressure coming 30 through the pipe A distributes under the perforated false bottom C and flows up through the numerous small openings in it up past and through the soap D in small cakes

about one inch by one inch by one fourth of an inch forming bubbles in the water E as 35 it passes through it. When the run is over and the pressure shut off the water runs down into the bottom of the tank and is drawn off through the valve or drain cock F.

In operation the pressure is first turned on 40 and thereafter the soap placed above the false bottom so as to cover it in a single layer of small pieces then the water placed in the tank above the false bottom and by regulating the temperature of the water the 45 amount of it and the pressure of the gas any size bubbles desired are produced by this machine in large quantities of so dry a nature that they leave no appreciable dampness regardless of the quantity.

50 The soap "D" may be any ordinary soap which will make a lather.

I claim:

The combination in a bubble making machine of a tank or suitable container having 55 a false bottom with a plurality of small holes therein, means for introducing compressed air beneath said false bottom, and a solution of bubble making properties maintained above such false bottom, all substantially as set forth.

ESTEN BEELER.
